COMBINATION CLOTHES HOLDER

Everett Lorne Whenham, Los Angeles, Calif.

Application May 8, 1934, Serial No. 724,502

12 Claims. (Cl. 312—4)

My invention relates to a combination holder for supporting various wraps and garments.

The objects of my invention are:

First, to provide a device of this class in which the space ordinarily occupied by a clothes hook in a closet, or the like, is utilized for supporting also a woman's hat and a man's hat in substantially out of the way positions;

Second, to provide a novel means for enclosing a hat support, and further an enclosing means which is suspended from means thereabove, which latter means forms also an upper hat support;

Third, to provide novel means of supporting and securing the enclosure or curtain whereby the same is readily attached or detached;

Fourth, to provide a device of this class in which the upper hat support and curtain are readily detached; so that the parts may be more readily nested and packed for shipment;

Fifth, to provide a novel and simple hat support made from a wire coil;

Sixth, to provide simple and novel means in connection therewith for supporting ties, or the like;

Seventh, to provide simple and novel means in connection therewith for supporting gloves, or the like; and

Eighth, to provide a device of this class which, as a whole, is simple and economical of construction, and durable.

With the above objects in view, I have devised a combination clothes holder having certain novel features of construction, as will be hereinafter described in detail and particularly set forth in the appended claims, reference being had to the accompanying drawings and to the characters of reference thereon, which form a part of this application, in which:

Fig. 1 is a perspective view of my device in its preferred embodiment, showing the enclosing curtain of the lower hat support partly pushed back;

Fig. 2 is a side elevational view on a reduced scale, showing the front portion of the curtain removed to facilitate the illustration; and

Fig. 3 is an enlarged fragmentary sectional elevation taken at 3—3 of Fig. 2.

Fig. 4 is a fragmentary perspective view of the upper portion of a slightly modified form of construction of my device;

Fig. 5 is a fragmentary perspective view of the upper portion of another modified construction, portions being broken away and in section to facilitate the illustration; and,

Fig. 6 is a sectional view thereof, taken sub-

stantially on the plane designated 6—6 in Fig. 5.

Like characters of reference refer to similar parts and portions throughout the views of the drawings.

In the device illustrated in Figs. 1, 2, and 3, of 5 the drawings, a unitary vertical support 1 is provided at the back of the device for securing the same to a wall, or the like. At the lower end of the support is a clothes hook 2 which may be of ordinary construction and made an integral 10 part of the vertical support. The vertical support is made up of a pair of wires or rods which are bent forwardly at their upper ends, forming an arm, as indicated by 3. Secured to and extending upwardly from the arm 3 is a hat support 4 formed of a wire coil in convex shape. Below the hat support 4 is another hat support 5, also formed of a wire coil in convex form. This latter coil is supported at its apex, by means of a wire arm 6 on the vertical support 1, the 20 arm being secured at its lower end between the wires or rods of the vertical support immediately above the hook 2. This arm extends outwardly and upwardly at an angle and in curved form, supporting the hat support 5 a considerable 25 distance below the hat support 4.

To the forward end of the arm 3 and between the two wires or rods forming the same is secured an arm 11a at the forward end of which is secured a ring 11. This ring extends backwardly 30 as a complete circular loop underneath the arm 3, being provided at its forward end with a hook 11b which is removably hooked over the forward end of the arm 11a. The curtain 12 is provided at the upper end with a hem 12a 35 through which the ring extends, the curtain being drawn over the hook end 11b of the ring. Thus the curtain is draped from the ring over and around the hat support 5. The upper portion of the curtain within the hem is shirred together and may be held up by a hook 3a at the central portion of the ring and on the arm 3. The lower end of the curtain may be provided with a draw string 13 for tying together the curtain below the hat placed on the support 5. 40

The hat support 5 is so constructed that it will support a hat within the crown thereof and is therefore particularly adapted for supporting a woman's hat. The diametrically extending portion or arm 3 and the ring 11 are adapted to 45 support the brim of a man's hat while the part 4 is adapted for locating the hat against lateral movement. Thus the ring supports the brim of the hat as well as the curtain for the lower hat support. 50

At the upper end of the vertical support 1 is secured a necktie support 21 which consists of a plurality of wire-formed arms 21a secured to the vertical support 1 and extending laterally to the opposite sides thereof.

Below the necktie support and secured to the portion 1 is a glove support 22 which consists mainly of a horizontal member positioned forwardly of and transversely to the vertical support. 10 One end thereof is secured to the portion 1 by a diagonal arm 22a extending laterally and downwardly therefrom.

In the modified form, shown in Fig. 4, the forwardly extending arm is similar to the arm 3 15 and it is made of two separate wires or rods 3b and 3c. To the forward end of the wire 3b is secured a ring similar to the ring 11, at one end of the split portion therein. The ring extends backwardly underneath the arm 3b, 3c and is 20 connected at its other forward end by a removable hook 11b, as described above. In this instance the upper portion of the curtain 12 is also provided with a hem similar to the hem 12a through which the ring 11 extends; but the opposite sides of the curtain are connected by a top curtain portion, which is provided at the middle between said opposite sides and diametrically thereacross with a hem 12c through which the wire 3c extends.

30 In this modification I have also shown hat positioning means 31 which consists of a plurality of arched wires secured together at their median portions, forming a substantially convex hat positioning means.

35 In Figs. 5 and 6 the upper hat support is a frame 41 which is substantially of the shape of a hat. The frame consists of a ring 41a and a plurality of slightly spaced apart wires or rods 41b, which are secured at one end to the ring 40 and extend radially inwardly, thence upwardly to form a crown, and are secured at the inner and upper ends to a small ring 41c. Through this ring and through an eye 42a at the upper and forward end of an arm 42, which extends forwardly of the vertical support 1, extends a bolt 43 for detachably securing the hat support 41 in place. Such detachable mounting permits ready nesting of the several parts for shipment.

The curtain 51, in this instance, is placed over 50 the top of the frame 41 and portions 51a inserted between the spaced apart rods or wires and such inwardly directed portions sewed together. The curtain is draped over the ring as in the other structures described.

55 Though I have shown and described a particular structure, and certain modifications thereof, I do not wish to be limited to these, but desire to include in the scope of my invention the construction, combination and arrangement substantially as set forth in the appended claims.

I claim:

1. In a device of the class described a unitary vertical support, a hat support extending outwardly and upwardly from the lower end 65 thereof, a second hat support extending outwardly from the upper end thereof and positioned over the first hat support, and a curtain depending from the lateral portion of the second hat support over and around the first hat support.

2. In a device of the class described, a unitary vertical support, a hat support extending outwardly and upwardly from adjacent the lower end thereof, a second hat support extending outwardly from the upper end thereof and posi-

tioned over the first hat support, a curtain depending from the lateral portion of the second hat support over and around the first hat support, and means at the lower end of the curtain shirring the lower end under the first hat support. 5

3. In a device of the class described, a unitary vertical support, a hat support extending outwardly and upwardly from the lower portion of the vertical support, a second hat support extending outwardly from the upper end of the vertical support and having at its center a raised portion and at its periphery a separable ring, and a curtain having at its upper end a hem through which the ring extends for supporting the curtain in draped form over and around the 15 second hat support.

4. In a device of the class described a vertical support having means for securing the same to a wall and having a clothes hook at the lower end, a hat support extending outwardly and upwardly 20 from the vertical support adjacent the hook, a second hat support extending outwardly from the upper end of the vertical support and positioned over the first hat support, and a curtain depending from the lateral portion of the second 25 hat support and over and around the first hat support.

5. In a device of the class described, a unitary support, a hat support extending outwardly from adjacent the lower end thereof, a second hat support 30 extending outwardly from the upper end thereof and comprising a ring and an upwardly extending portion at its middle for positioning a hat on the ring against lateral displacement, and a curtain depending from the ring over and 35 around the first hat support.

6. In a device of the class described, a hat support, an arm rising from said support and extending transversely with respect thereto, a separable ring directly below said transverse arm 40 portion and so positioned relative thereto that the transverse arm portion extends diametrically across the ring, one end of the ring being supported by said transverse arm portion, the other end of the ring having a hook by means of 45 which the separable ends of the ring are connected, and a curtain having a hem at the top through which the ring extends, said curtain having its top portion extended to cover the space within the ring, said extended top portion being 50 supported by said transverse portion of the arm.

7. In a device of the class described, a support, a hat-shaped frame supported by the support, said frame comprising an outer ring and pairs of 55 slightly spaced apart rods extending radially inwardly from the ring and upwardly at the middle of the ring, and a curtain positioned over the frame with portions extending between said pairs of rods and secured in such position, the curtain 60 draping over the outer side of the ring.

8. In a hat support in combination, a support, a hat support carried by said support and comprising, a ring on which to rest the brim of a hat, elements rising within the ring and shaped to 65 support the crown of the hat, and a curtain attachable to said ring.

9. In a hat support in combination, a support, a hat support carried by said support and comprising, a ring on which to rest the brim of a hat, 70 elements rising within the ring and shaped to support the crown of the hat, and a curtain held detachably suspended from said ring, said curtain having a portion covering the space within the ring.

10. In a device of the class described, a support, an arm extending outwardly therefrom, a separable ring secured to said arm in such position that the arm extends diametrically above
5 the ring, one separable end of the ring having means for detachably connecting the separable ends of the ring, and a curtain having a hem at its upper portion through which the ring removably extends.
- 10 11. In a device of the class described, a clothes hook, an arm extending upward from and supported by said hook, said arm forming a right angle, a hat support secured to the lower portion of said arm adjacent the said hook, means
15 secured upon the free end of said arm for sup-

porting a curtain capable of being draped around said hat support above the clothes hook, for enclosing said hat support but not the hook and the said arm.

12. In a device of the class described, a vertical clothes holder having a clothes hook at its lower end and a horizontal arm at the top, a rod extending upwardly and outwardly from said holder, a hat support at the upper end of the rod, supporting means on said arm, and a curtain 10 suspended by the supporting means of the arm from above the hat support and draped there-around, said curtain being positioned in front and free of the clothes holder and hook.

EVERETT LORNE WHENHAM. 15
